UNITED STATES PATENT OFFICE.

ARTHUR F. HODGSON, OF JARVIS, ONTARIO, CANADA.

HONEY EXTRACTOR.

Application filed June 9, 1927. Serial No. 197,686.

My invention relates to improvements in honey extractors with more particular reference to that type in which the combs are positioned in a rotor with their planes vertical and disposed radially of the rotor and in which extraction is carried out simultaneously from both sides of the comb and the object of the present invention is to provide an improved extractor of this type in which 5 the operation of loading and unloading may be greatly simplified and expedited thus obtaining a valuable saving in labor and time; a further object is to provide an improved construction for the rotor and the manner 10 of mounting and supporting the combs therein whereby the tendency to damage the frail comb structure during extraction is greatly reduced; a further object is to provide a very reliable and secure manner of holding 15 the combs in the rotor during extraction so that they cannot shift from their proper positions therein; a further object is to devise such an extractor which will be of simple and inexpensive construction and which will 20 have large capacity; and a still further object is to provide a novel form of comb container for use in this type of extractor which will possess many advantageous features and which may also be used for straining honey 25 from cappings in this type of extractor.

Further objects will appear in the course of the following specification.

My invention consists in the construction and arrangement of parts, all as hereinafter 30 more particularly described and illustrated in the accompanying drawings in which:—

Fig. 1 is a horizontal section of an extractor constructed in accordance with my invention showing the extractor loaded with 35 combs ready for extraction, the section being taken on the line 1—1 of Fig. 2 looking downwardly in the direction of the arrows.

Fig. 2 is a central vertical section taken on the line 2—2 of Fig. 1 looking in the direction of the arrows.

Fig. 3 is a top plan view of a circular base plate forming part of the rotor used in the form illustrated in Figs. 1 and 2, the position of one of a number of comb containers supported in the rotor upon said base plate being indicated in broken lines.

Fig. 4 is a perspective view of a novel form of comb container used in my invention.

Fig. 5 is a detached fragmentary vertical 50 section of a portion of the rotor shown in

Figs 1 and 2 showing a comb container and the position of a comb therein, the section being taken on the line 5—5 of Fig. 1,

Fig. 6 is a top plan view of one of my comb containers showing a perforated sieve 60 which may be detachably connected thereto in order to strain the honey from cappings as will be later referred to.

Fig. 7 is a front elevation of Fig. 6 looking in the direction of the arrow.

Fig. 8 is a central, vertical section taken similarly to Fig. 2 and illustrating a slightly modified construction for the rotor.

Fig. 9 is a horizontal section taken on the line 9—9 of Fig. 8 looking in the direction 70 of the arrows.

In the drawings, like characters of reference indicate corresponding parts in the various views.

Reference will first be made to the construction shown in Figs. 1 to 5 inclusive.

In this form my improved extractor comprises a cylindrical tub or casing 10 which is open at the top and is provided with any suitable bottom 11 which in the form shown 80 is dished upwardly.

A cross member 12 extends diametrically across the top of the casing and is suitably secured in position.

A vertical shaft 13 is mounted axially within the casing and a suitable thrust bearing 14 is provided for the lower end thereof. This shaft is journaled within the cross bar 12 which bar provides a bearing for the upper end of the shaft.

Secured to the shaft 13 within the casing 10 is a rotor which will be referred to collectively by the numeral 15.

This rotor comprises a circular base plate 16 fixedly secured to the shaft 13 adjacent 95 to the lower end thereof and in spaced relation above the bottom of the casing 1 so that a honey space 17 is provided therebelow.

The plate 16 is solid throughout, that is it has no openings therein except the central 100 opening 18 for the shaft 13. The purpose of this feature will be later referred to.

Upon the upper face of the plate 16 are six raised portions 19 equally spaced circumferentially about the plate. These raised 105 portions 19 form positioning or locating means for comb containers as will later be explained.

Upper and lower flanged fittings 20 and 21 are fixedly secured upon the shaft 13 and 110

extending from these fittins are radial arms or spokes 22, the spokes being positioned vertically above the raised portions 19 on the base plate 16.

5 Upper and lower annular bands 23 and 24 are carried by the outer ends of these spokes 22.

10 The rotor 15 comprises the shaft 13, base plate 16, flanged fittings 20 and 21, spokes 22 and the annular bands 23 and 24 and this rotor is rotatably mounted within the casing 10 for rotation about a vertical axis.

15 Any suitable means for rotating the shaft 13 may be provided and this has been merely indicated diagrammatically by the friction discs 25 and 26 and the drive shaft 27 and pulley 28.

20 Also any suitable brake mechanism for the rotor may be employed and this is merely indicated diagrammatically by the numeral 29.

25 Six comb containers 30 are employed and these are removably supported within the rotor.

30 Each container 30 is formed with two arcuate end walls 31 which may be made of wood.

35 The rear and side walls 32 and 33 respectfully are of sheet metal and may be in a single piece.

40 The construction of the container is such that it is open on its front face, which is that of greater radius and is entirely enclosed on all other faces so that no air may enter the container except over the front face. The purpose of this will be later explained.

45 Secured upon the inner faces of the end walls 31 of each container are a number of spaced apart protuberances in the form of raised strips or bars 34.

50 The sides of these bars 34 are tapered towards the rear wall 32 of the container so that parallel sided grooves 35 are formed between adjacent bars. Also the bars in the top and bottom end walls are vertically above each other so that the grooves 35 are also vertically above each other.

55 There are eight grooves 35 provided at each end wall so that each container will accommodate eight combs.

60 To the upper end wall 31 of each container is secured a handle 36.

65 An outlet tap 37 for the extracted honey is provided at the bottom of the casing 10.

70 In the modification shown in Figs. 8 and 9 the construction is much the same except that in this case an annular shield 38 is carried by the rotor which shield is of gradually increasing diameter from top to bottom.

75 In this case the lower end of this shield is secured about the periphery of a base plate 39 and in order to provide means for the extracted honey to pass downwardly the

base plate in this case is formed with recesses 40. This base plate 39 in this case is similar to the base plate 16 used in the form shown in Figs. 1 and 2 except that it is formed with the recesses 40.

80 Also in this case only one set of spokes 22 are required, which spokes support the upper end of the shield 38.

85 In this form spacing rings 41 and 42 are carried upon the inner face of the shield 38 the purpose of which will be described hereinafter.

90 In other respects the construction in Figs. 8 and 9 is the same as that already described.

95 In Figs. 6 and 7 is illustrated a fitting whereby my containers may be used for straining honey from cappings in my extractor.

100 This fitting consists of a perforated sieve 43 the vertical edges of which are bent at 44 to form slips by which the sieve may be detachably mounted upon the container so as to cover the open front face thereof.

105 At the top and bottom of the sieve 43 spacing or filler strips 45 are secured to the outer face of the sieve (see Figs. 6 and 7) so as to form raised portions projecting from the outer face of the sieve, the purpose of which will later be explained.

110 The construction and operation of my device is as follows.

115 In loading the containers 30 with the combs, the container is laid upon its rear face with the open front face upward and the combs as they are uncapped are inserted into the container. The bottom of the comb enters first and the grooves 35 form guides for the ends of the comb frame.

120 When fully inserted into the container, the overhanging portions of the top bar 46 of the comb frame strikes against the edges of the end walls 31 of the container (see Fig. 5) so that the top bar 46 of the comb projects slightly beyond the front face of the container.

125 This is clearly shown in Figs. 1-2-5 and 8.

130 Since the container 30 is entirely closed on all but the front face and is leak proof to honey it is very convenient and economical in loading since all drip from the uncapped combs is caught therein.

135 When the container is full of combs, it is raised into the upright position shown in Fig. 4 and lifted by the handle 36 and inserted downwardly into its position within the rotor.

140 The disposition of the various parts is such that when the filled container is in position within the rotor, it is firmly held in position and cannot shift at all.

145 The annular strips 23 and 24 engage the top bars 46 of the combs and hold them against radial movement outward and the protuberances 19 upon the base plate 16, and the spokes 22 hold the container against cir-

cumferential movement. Also the annular strips 23 and 24 prevent radial movement outwardly of the container.

In this way the containers and also the 5 combs therein are held firmly in place in the rotor and cannot move under the action of centrifugal force as the rotor rotates during extraction.

As the rotor is rotated the honey is extracted from both sides of the combs simultaneously.

A very valuable feature of my invention lies in the fact that the containers are completely closed to the admission of air thereinto on all faces except the front face through which open front face the extracted honey is discharged.

Hitherto one of the great troubles with extractors of this type has been the breakage 20 of the comb structure and this has been due in a great measure to the rush of air over the cell structure during extraction. The rotor has functioned like a blower and there has been a violent rush of air outwardly 25 between the combs, the cell walls acting like small sails.

This has been entirely overcome in my machine, since absolutely no air can enter the container from either the sides, ends or rear and the result of this is that the combs are rotating during extraction in perfectly still air. This is a most important improvement.

The bad effects of this blower action is still further eliminated in my construction by having the base plate 16 of the rotor without openings in the central portion thereof as this solid plate prevents any circulation of air vertically through the rotor.

40 A further feature of this construction is that under the action of centrifugal force air in my containers becomes rarefied which greatly aids extraction.

When extraction is complete the containers are lifted from the rotor and the extracted combs removed therefrom.

By providing a duplicate set of containers, when one set is being used in the extractor, the operator could be employing his time in loading the second set and thus a valuable saving in time would be made. It does not matter how long the capped combs remain in the containers before they are placed in the extractor since all drip is caught and held in the leak proof container.

60 In the operation of the modified form shown in Figs. 8 and 9 the operation is much the same except that the shield 38 is provided and this shield is tapered outwardly towards the bottom so that the action of centrifugal force tends to accelerate the flow of extracted honey downwardly over this shield.

In using my container to strain honey 65 from cappings, the container is laid on its

rear face as before and filled with cappings. The sieve 43 is then placed thereon to cover the open front face of the container and the containers are inserted into the rotor as already explained.

In this case, since the thickness of the sieve 43 would not be as great as that of the top bars 46 of the comb frames, it will probably be necessary to make up for this difference by providing spacing or filler strips 45 75 so that the thickness of the sieve 43 and filler strips 45 as indicated by the arrows A in Fig. 6 will be equal to the distance by which the top bar 46 of the comb normally projects beyond the front face of the container.

This is necessary so that the annular bands 23 and 24 of the rotor (see Figs. 2 and 5) will contact with the filler strips 45 in order to hold the containers firmly in position 85 within the rotor. In other words the thickness of the sieve and filler strips 45 is together equal to the thickness of top bar 46 of the comb.

From the foregoing it will be evident that 90 I have devised improvements in honey extractors whereby the objects of my invention have been attained.

Various modifications may be made in my invention without departing from the spirit 95 thereof or the scope of the claims and therefore the exact forms shown are to be taken as illustrative only and not in a limiting sense and I desire, that only such limitations shall be placed thereon as are imposed by the prior art or are specifically set forth in the appended claims.

What I claim as my invention is:

1. In a honey extractor, a comb container therefor adapted to accommodate a plurality 105 of combs and comprising, end, side and rear walls completely closing said container to the passage of air thereinto on the respective faces thereof, the container being open over its front face, and comb holding means upon 110 the inner faces of the end walls of the container.

2. In a honey extractor, a comb container therefor adapted to accommodate a plurality 115 of combs and comprising, end, side and rear walls completely closing said container to the passage of air thereinto on the respective faces thereof, the container being open over its front face, and comb separating and positioning means upon the inner faces of 120 the end walls of the container.

3. In a honey extractor, a comb container therefor adapted to accommodate a plurality 125 of combs and comprising, end, side and rear walls completely closing said container to the passage of air thereinto on the respective faces thereof, the container being open over its front face, and spaced apart protuberances upon the inner faces of the end walls of the container, said protuber-

ances constituting comb separating and positioning means.

4. In a honey extractor, a comb container therefor adapted to accommodate a plurality of combs and comprising, end, side and rear walls completely closing said container to the passage of air thereinto on the respective faces thereof, the end walls being of arcuate shape, the front face of the container being that of the greater radius and being open, radially disposed, spaced apart, raised bars upon the inner faces of the end walls, adjacent bars forming grooves therebetween.

15. 5. In a honey extractor, a comb container therefor adapted to accommodate a plurality of combs and comprising, end, side and rear walls completely closing said container to the passage of air thereinto on the 20 respective faces thereof, the end walls being of arcuate shape, the front face of the container being that of the greater radius and being open, radially disposed, spaced apart, raised, tapered bars upon the inner faces of 25 the end walls, adjacent bars forming parallel sided grooves therebetween.

6. In a honey extractor, in combination, a casing, a rotor mounted therein for rotation about a vertical axis, a plurality of 30 comb containers removably supported within the rotor and disposed circumferentially about the rotor, each container adapted to accommodate a plurality of combs therein with their planes vertical and disposed 35 radially, and means for positioning the containers both radially and circumferentially within the rotor.

7. In a honey extractor, in combination, a casing, a rotor mounted therein for rotation 40 about a vertical axis, a plurality of comb containers removably supported within the rotor and disposed circumferentially about the rotor, each container adapted to accommodate a plurality of combs therein 45 with their planes vertical and disposed radially, each container being open over the face thereof which is directed radially outward and closed to the passage of air thereinto on all other faces, and means for positioning the containers both radially and circumferentially within the rotor.

8. In a honey extractor, in combination, a casing, a rotor mounted therein for rotation about a vertical axis, a plurality of 55 comb containers removably supported within the rotor and disposed circumferentially about the rotor, each container adapted to accommodate a plurality of combs therein with their planes vertical and disposed 60 radially, each container being open over the face thereof which is directed radially outward and closed to the passage of air thereinto on all other faces, means for positioning the containers both radially and circumferentially within the rotor, and means

for retaining the combs in position within the containers.

9. In a honey extractor, in combination, a casing, a rotor mounted therein for rotation about a vertical axis, a plurality of combs 70 containers removably supported within the rotor, each container being of arcuate shape as viewed from above and said containers disposed circumferentially about the rotor with the faces of greater radii directed outwardly, each container adapted to accommodate a plurality of combs with their planes disposed vertically and radially, and means for positioning the containers both radially and circumferentially within the rotor. 80

10. In a honey extractor, in combination, a casing, a rotor mounted therein for rotation about a vertical axis, a plurality of comb containers removably supported within the rotor, each container being of arcuate shape as viewed from above and said containers disposed circumferentially about the rotor with the faces of greater radii directed outwardly, said outwardly directed faces of the containers being open and the 90 containers being closed to the passage of air thereinto on all other faces, each container adapted to accommodate a plurality of combs with their planes disposed vertically and radially, and means for positioning the containers both radially and circumferentially within the rotor. 95

11. In a honey extractor, in combination, a casing, a rotor mounted therein for rotation about a vertical axis, a plurality of 100 comb containers removably supported within the rotor and adapted for insertion thereinto from the top thereof, a handle at the upper end of each container, each container being of arcuate shape as viewed from above 105 and said containers disposed circumferentially about the rotor with the faces of greater radii directed outwardly, said outwardly directed faces of the containers being open and the containers being closed 110 to the passage of air thereinto on all other faces, each container adapted to accommodate a plurality of combs with their planes vertical and disposed radially within the rotor, means for positioning the containers 115 both radially and circumferentially within the rotor, positioning means for the combs at the top and bottom ends of the containers, and means for preventing movement of the combs radially outwardly. 120

12. In a honey extractor, in combination, a casing, a rotor mounted therein for rotation about a vertical axis, a plurality of comb containers removably supported within the rotor and adapted for insertion thereinto 125 from the top thereof, a handle at the upper end of each container, each container being of arcuate shape as viewed from above and said containers disposed circumferentially about the rotor with the faces of greater radii di- 130

rected outwardly, said outwardly directed faces of the containers being open and the containers being closed to the passage of air thereinto on all other faces, each container 5 adapted to accommodate a plurality of combs with their planes vertical and disposed radially within the rotor, means for positioning the containers both radially and circumferentially within the rotor, positioning means for the combs at the top and bottom ends of the containers, and means extending circumferentially about the rotor and across the outer open faces of the containers, said means engaging the combs in 10 the containers to prevent movement radially outward thereof.

13. In a honey extractor, in combination, a casing, a rotor mounted therein for rotation about a vertical axis, a plurality of comb 20 containers removably supported within the rotor and adapted for insertion thereinto from the top thereof, a handle at the upper end of each container, each container being of arcuate shape as viewed from above and 25 said containers disposed circumferentially about the rotor with the faces of greater radii directed outwardly, said outwardly directed faces of the containers being open and the containers being closed to the passage of 30 air thereinto on all other faces, each container adapted to accommodate a plurality of combs with their planes vertical and disposed radially within the rotor, means for 35 positioning the containers both radially and circumferentially within the rotor, positioning means for the combs at the top and bottom ends of the containers, and an annular strip 40 extending circumferentially about the rotor and across the outer open faces of the containers, said strip engaging the combs in the containers, to prevent movement radially outward thereof.

14. In a honey extractor, in combination, a casing, a rotor mounted therein for rotation about a vertical axis, said rotor comprising 45 a horizontally disposed circular base plate, a plurality of comb containers removably supported upon said base plate, each container being of arcuate shape as viewed from above and said containers disposed circumferentially about the base plate with the faces of greater radii directed outwardly and means for positioning the containers both radially and circumferentially within the rotor.

50 15. In a honey extractor, in combination, a casing, a rotor mounted therein for rotation about a vertical axis, a plurality of comb containers removably supported within the rotor and adapted for insertion thereinto from the top thereof, a handle at the upper end of each container, each container being of arcuate shape as viewed from above, said containers disposed circumferentially about the rotor with the faces of greater radii directed 55 outwardly, said outwardly directed

faces of the containers being open and the containers being closed to the passage of air thereinto on all other faces, each container adapted to accommodate a plurality of combs with their planes vertical and disposed radially within the rotor, means for 70 positioning the containers both radially and circumferentially within the rotor, positioning means for the combs at the top and bottom ends of the containers, an annular shield carried by the rotor and extending thereabout, said shield spaced radially outward from the outer faces of the containers and extending the entire height of the containers, and spacing rings carried by the inner face 75 of said shield and extending circumferentially thereabout, said rings engaging the combs in the containers to prevent radially outward movement thereof.

16. In a honey extractor, in combination, a casing, a rotor mounted therein for rotation about a vertical axis, a plurality of comb containers removably supported within the rotor and adapted for insertion thereinto from the top thereof, a handle at the upper end of each container, each container being of arcuate shape as viewed from above, and said containers disposed circumferentially about the rotor with the faces of greater radii directed outwardly, said outwardly directed faces of the containers being open and the containers being closed to the passage of air thereinto on all other faces, each container adapted to accommodate a plurality of combs with their planes vertical and disposed radially within the rotor, means for 90 positioning the containers both radially and circumferentially within the rotor, positioning means for the combs at the top and bottom ends of the containers, an annular shield 95 carried by the rotor and extending thereabout, said shield spaced radially outward from the outer faces of the containers, and extending the entire height of the containers, said shield being of gradually increasing diameter from the top to the bottom thereof, and spacing rings carried by the inner face 100 of said shield and extending circumferentially thereabout said rings engaging the combs in the containers, to prevent radially outward movement thereof.

17. In a honey extractor, a removable container open on one face and entirely enclosed and leak proof to honey on all other faces, and a perforated sieve element detachably 110 mounted upon the container and extending over said open face.

18. In a honey extractor, a removable container open on one face and entirely enclosed and leak proof to honey on all other faces, a perforated sieve element detachably mounted upon the container and extending over said open face, and a spacing strip attached to the outer face of said sieve element.

ARTHUR F. HODGSON.
